UNITED STATES PATENT OFFICE

133,453

DESIGN FOR A COMBINED WASHING MACHINE AND WRINGER

Paul Schweikher, Chicago, Ill., assignor to Nine-
teen Hundred Corporation, St. Joseph, Mich.,
a corporation of Michigan

Application December 14, 1940, Serial No. 97,300

Term of patent 7 years

To all whom it may concern:

Be it known that I, Paul Schweikher, a citizen of the United States and a resident of the city of Chicago, in the county of Cook and State of Illinois, have invented a new, original, and ornamental Design for a Combined Washing Machine and Wringer, of which the following is a specification, reference being had to the accompanying drawings, forming a part thereof.

On the drawings:

Figure 1 is a perspective view of a combined washing machine and wringer showing my new design; and

Figure 2 is a top plan view thereof with the legs omitted for convenience of illustration.

The characteristic features of the design reside in the combined washing machine and wringer disclosed, in which the ring, the legs, and the vertical bead-like projections adjacent the legs, have the configuration shown.

I claim:

The ornamental design for a combined washing machine and wringer, as shown and described.

PAUL SCHWEIKHER.
